UNITED STATES PATENT OFFICE.

MARK L. ROBERTS, OF MOUNT UNION, OHIO.

KNITTING-MACHINE.

Specification forming part of Letters Patent No. 31,404, dated February 12, 1861; Reissued December 22, 1868, No. 3,242.

To all whom it may concern:

Be it known that I, MARK L. ROBERTS, of Mount Union, in the county of Stark and State of Ohio, have invented a new and useful Improvement in Knitting - Machines; and I do hereby declare that the following is a full, clear, and exact description of the construction and operation of the same, reference being had to the annexed drawings, 5 making a part of this specification, in which—

Figure 1, is a vertical longitudinal section of part of the machine, having the improvement applied; and Fig. 2, a sectional front 15 view of part of the same.

Like letters, when on the different figures, indicate the same objects.

My invention consists in the peculiar arrangement, hereinafter described, of the 20 presser and its guides with the outside of the face of the needle-cylinder, or carrier; whereby the stitches are pressed downward more certainly, and thus prevented from being slipped out of the eyes of the needles as 25 the latter are pushed forward in the operation of knitting.

In the drawings, A, is the frame of the machine; B, the needle-carrier; C—C, the needles; D, the needle-operator; E, the 30 crank; F, the connecting rod; G, the presser, and G', G', its stationary guides.

The needle-carrier (B) has a deep, straight, rectangular, independent groove *i*, for each one of the numerous needles (C), 35 the said grooves being cut parallel with each other along the periphery of the carrier, as seen in Fig. 1, and at equal distances apart, as seen in Fig. 2, the said grooves and their distances apart being represented in the 40 drawings as of the regular working size.

The needles C—C—two only being shown—are, in this instance, made with a spring-closing eye or loop, as in Hollen's patent, but instead of extending the stem 45 back and then forward so as to form an upper stem to work in the notches of a steady-ing-wheel for support, as heretofore, they are made single at their rear ends, as seen in Fig. 1, the said end being simply bent up 50 as seen at *k*, which produces, not only the stud whereby the operator (D) slides the needle forward and back, but serves, in combination with the sides of the groove (*i*) as a perfectly sufficient means for support- 55 ing the needle in proper position in the

said groove. A wire tie, *l*, is let into the carrier, transversely, as seen in the drawings, merely for the purpose of keeping the needles from falling out from the under side, and not to bind them in the grooves 60 (*i*—*i*). The said needles can therefore be inserted or withdrawn, as occasion may require, with the greatest facility.

The operator (D) is simply a block of metal grooved so as to fit around, and slide 65 upon, a stationary guide, D', and be attached to the connecting-rod (F), which is jointed at F', to a screw-stem F'', which is adjustably fixed to the said operator (D), by means of jam-nuts 3, 3, in the well known 70 manner seen in Fig. 1. The under side of the operator (D) has two broad projections 1, 1, which reach down nearly to the periphery of the needle-carrier (B), and alternately catch upon the studs (*k*) of the 75 needles, in operating them.

The presser (G) is a flat plate constructed so as to be capable of being slid up and down between the vertical stationary guides, G' G', (which are fixed to the frame (A)) 80 in close contact with the face end of the needle-carrier (B), its lower end being beveled so as to produce a chisel-edge next to the face of the carrier, and also slotted in its middle as seen at, 4, so that it may pass 85 clear of the needle, as it slides up and down in the guides (G' G'); the thin, beveled, edge may also be slightly serrated to prevent the possibility of the stitches or fabric from slipping from under it as it is pressed 90 down upon the same. Its vertical sliding motion is effected by means of the bent lever (M), which has its fulcrum at N, while its weight end passes loosely through a double-counter-sunk hole *o*, in the presser (D), as 95 seen in the drawings, and its power end rests upon either of the two cams (P P) on the crank-shaft 2, it being jointed at 2, so that it may be moved from one cam to the other as may be required in knitting to the 100 right and left.

The presser (G) is suspended between the guides (G' G'), by means of a spring (H) which draws it up, as the weight-end of the lever rises, so as to bring its beveled 105 edge above the needle—the cams (P, P,) acting on the lever (M) force it downward to produce the requisite pressure on the stitches.

Having thus fully described my improve- 110

ment and pointed out its utility, what I claim as new therein, and desire to secure by Letters Patent is—

The arrangement of the vertical guides, 5 G' G', and the presser G, with the said horizontal needle-cylinder B, so that the guides and presser shall be outside of the

face of the cylinder, substantially as described.

MARK L. ROBERTS.
